F. M. Jones,

UNITED STATES PATENT OFFICE.

FRANK M. JONES, OF DINUBA, CALIFORNIA.

MUSIC-LEAF TURNER.

1,179,325

Specification of Letters Patent. Patented Apr. 11, 1916.

Application filed November 6, 1915. Serial No. 60,093.

To all whom it may concern:

Be it known that I, FRANK M. JONES, a citizen of the United States, residing at Dinuba, in the county of Tulare and State of California, have invented new and useful Improvements in Music-Leaf Turners, of which the following is a specification.

The invention relates to music leaf turners, and more particularly to the class of automatic music leaf turners.

The primary object of the invention is the provision of a music leaf turner wherein the music turning arms are acted upon through the medium of springs which are successively released for the turning of the sheets of music in their order, thereby avoiding the handling of the said sheets for this purpose.

Another object of the invention is the provision of a turner of this character wherein the tension of the springs can be varied accordingly to the weight of the sheets of the music to assure the positive turning thereof when the music is in use.

A further object of the invention is the provision of a music leaf turner of this character wherein the construction thereof is novel in form for accuracy in the working thereof.

A still further object of the invention is the provision of a music leaf turner of this character which is simple in construction, reliable and efficient in its operation, strong, durable, and inexpensive in manufacture.

With these and other objects in view, the invention consists in the construction, combination and arrangement of parts as will be hereinafter fully described, illustrated in the accompanying drawings, and pointed out in the claim hereunto appended.

40 In the drawings:—

Figure 1 is a front elevation of the music leaf turner constructed in accordance with the invention. Fig. 2 is a top plan view thereof. Fig. 3 is an end elevation. Fig. 4 is a sectional view on the line 4—4 of Fig. 1. Fig. 5 is a sectional view on the line 5—5 of Fig. 1. Fig. 6 is a vertical transverse sectional view of the lower part of the mechanism.

50 Similar reference characters indicate corresponding parts throughout the several views in the drawings.

Referring to the drawings in detail, the music leaf turner comprises a frame A including upper and lower plates 10 and 11 respectively, which are held in spaced par-

allel relation and united through the medium of vertical columns or posts 12 at the ends thereof, while journaled in these plates is a plurality of spaced vertical shafts 13, in the upper ends of which are fixed the stems 14 of horizontally disposed music leaf turning arms 15, while loosely surrounding these shafts are sleeves 16 each having loosely coiled about the same tension spring 17, one end of each of which is fixed in the shaft 13 above the sleeve mounted thereon, while its opposite end is connected to a tightening chain 18 wrapped about the said sleeve 16, and these chains are connected to an adjusting bar or rod 19 which is slidably mounted in guides 20, one of which is formed with a keeper 21 with which is adapted to engage a latch nib 22 formed on the rod or bar 19 so as to lock the same in position for holding the spring under high tension, the outer end of the rod or bar 19 being formed with a finger knob 23 so that it can be readily and easily adjusted to vary the tension of the springs 17 for a purpose presently described. The sleeve 16 on the shaft 13 can be supported from slipping downwardly in any suitable manner.

Formed on or fixed to the lower ends of the shafts 13 are ratchet wheels 24 with each of which engages a locking pawl or dog 25 which is held in locking position through the medium of a leaf spring 26 acting thereon and suitably fixed to the lower plate 11 of the frame. These dogs or pawls 25 are released through the medium of push rods 27 connected thereto and slidable through a front plate 28 mounted on the frame, the outer ends of the rods being formed with finger buttons 29 so that they can be pushed inwardly for releasing the dogs or pawls 25 to free the shafts 13 which are acted upon by the tension of the springs 17 for the turning of the music leaf turning arms 15 which carry fingers 30, each being adapted to lie against the sheet at the back thereof when at the right hand side of the music leaf turner so as to work against the sheet when the arm 15 swings to push the sheet during the turning of the arm, thereby avoiding the wrinkling of the sheet should the arm be connected thereto by a clip or otherwise. It will be apparent that the finger slides over the face of the sheet during the turning thereof on the swinging of the arm 15.

2
Fixed to the upper plates 10 and rising therefrom is a vertical standard 31 to which is connected a brace 32, the same being also connected to the frame, and upon this standard 31 is connected one end of a holding cord 33 having at its free end a ring 34 which is adapted for detachable engagement with a keeper hook 35 also mounted in the standard 31 at the upper end thereof, and this cord 33 is adapted to bridge the music at the line of fold of the sheets thereof so as to hold the same fastened in position upon the music leaf turner.

The tension of the springs 17 is varied so as to assure the positive turning of the sheets of the music when connected thereto irrespective of the weight thereof.

In the use of the music leaf turner the music is hung upon the standard 31 by the cord 33, and the leaves thereof are attached to the turning arms 15, it being understood of course that the shafts 13 are locked against rotation by the dogs or pawls 25 engaging the ratchet wheels 24, and when these shafts are locked the springs 17 are under tension so that by releasing the pawls 25 the shafts will be released from under tension of the springs from right to left for the swinging of the arms 15 in this direction, thereby turning the sheets of the music in successive order.

From the foregoing description, taken in connection with the accompanying draw-

ings, the construction and manner of operation of the device will be clearly understood, and therefore a more extended explanation has been omitted.

What is claimed is:—

A music leaf turner comprising a support, a vertical shaft journaled in said support, a music leaf turning arm operated by said shaft, a sleeve loosely surrounding the shaft, a coiled tension spring encircling said sleeve and having one end fixed to the shaft, a ratchet disk fixed to the shaft, a ratchet pawl pivoted in the support and engaging the ratchet disk, a spring acting upon the pawl to hold the same in normal locking engagement with the disk, a push rod connected with the ratchet pawl for moving the same to release the disk, a rod horizontally disposed in the support and slideable therein, a chain connected with the last named rod and to the other end of the spring, a keeper on the support and a nib formed on the last named rod for locking engagement with the keeper to hold said rod in adjusted position and thereby increase or decrease the tension of the spring.

In testimony whereof I affix my signature in presence of two witnesses.

FRANK M. JONES.
